UNITED STATES PATENT OFFICE.

ELSAMUR S. FRENCH, OF DENVER, COLORADO.

EXHIBITION DEVICE FOR ARTICLES HAVING CASTERS.

1,168,719.

Specification of Letters Patent. Patented Jan. 18, 1916.

Application filed January 16, 1915. Serial No. 2,741.

To all whom it may concern:

Be it known that I, ELSAMUR S. FRENCH, a citizen of the United States, residing at Denver, in the county of Denver and State 5 of Colorado, have invented certain new and useful Improvements in Exhibition Devices for Articles Having Casters; and I do hereby declare the following to be a full, clear, and exact description of the invention, such 10 as will enable others skilled in the art to which it appertains to make and use the same.

This invention relates to devices for the exhibition of furniture or other articles 15 having casters and especially for bedsteads and the like and has for an object to provide a track for guiding the casters in the desired direction and having an improved construction for receiving the casters into 20 said track.

With these and other objects in view the invention comprises certain novel constructions, combinations and arrangements of parts as will hereinafter be more fully described and claimed and as shown in the 25 accompanying drawings in which like characters of reference indicate corresponding parts throughout the several views and in which—

30 Figure I is a plan view of my invention. Fig. II is a side elevation of my invention showing a portion of the legs of a bedstead with casters in the track. Fig. III is a detail view of the receiving-end construction 35 of my track showing in full lines a caster about to enter the track and in dotted lines indicating the caster in position as at Fig. II. Fig. IV is a vertical section at line A—A Fig. III.

40 The common practice among furniture dealers in exhibiting sample bedsteads is to connect the head and foot sections of the bedstead by very short side bars (usually about a foot or less in length) so that the 45 two sections stand close together and the whole forms a rectangular figure in length equal to the width of the bed and about one foot or less in width. The bedsteads, thus put together, are usually ranged side by 50 side in long rows and as close together as possible in order to economize floor space. This arrangement necessitates the handling of the beds from one end only. In drawing one of the bedsteads from the row or in re- 55 placing it therein it is apt to collide with rub against the bedsteads adjoining on

each side, thus damaging the goods and delaying the work unless some track or guide is provided for the casters. For this purpose I provide a channel member 1 of suitable width for the reception of an ordinary caster and having screw holes 2 in the floor 1^a thereof or other suitable means for permitting it to be fastened to the floor and having closed end 3 for preventing the 60 movement of the caster beyond that end of the track.

At the receiving end of the track I bend down and flatten out one side 7 of the channel member as at 4 so that the same will be 65 flat upon the floor in order that the caster may easily roll thereupon. The bending of the side as at 4 leaves a slanting guiding edge at 5 which serves to guide the caster into the track should the caster be run 70 against the same. Likewise should the 75 caster be run against the upstanding side 6 of the channel as shown at Fig. III said side 6 will deflect and turn the caster into the track, in the position shown in Fig. II 80 and in dotted lines at Fig. III. In use these tracks will be attached to the exhibition floor parallel to each other and at intervals slightly in excess of the width of the bed- 85 stead as set up in exhibition form as above described and the casters of either the head or foot sections will be run into the track.

When it is desired to withdraw a particular bed it may be pulled out without danger of collision with adjoining beds as the track 90 keeps it at all times spaced away therefrom.

When it is desired to replace the bed one of the casters as 9, on the head section (for example) is rolled on to the open end of the track and, by the side 6 or guiding edge 95 5 is turned and guided into the track after which no further manual guiding of that 100 caster is required as it will follow the track. When the bed has been pushed along until the other head caster 8 approaches the open 105 end of the track, it likewise is rolled upon the floor 1^a and flat portion 4 and no further manual guiding is required as the side 6 or guiding edge 5 will guide it into the track.

While I have described my invention as used for bedsteads it is evident that it may likewise be used for any articles having casters.

I claim—

1. An exhibition device for articles having casters, consisting of a channel member

105

110

including a flat floor and upright sides, one side being bent down into the plane of the floor of the channel and for a distance from the open end of said channel.

- 5 2. An exhibition device for articles having casters, consisting of a channel member having one end thereof closed and the other end open and having sides extending from the closed end toward the open end, one side extending to the open end but the other side being shorter than the first mentioned side.
- 10 3. In an exhibition device for articles

having casters, a channel member having a closed end and sides extending therefrom toward the other end, one of said sides extending substantially to said other end but the other side being bent, at a point back from said other end, so as to form a slanting guide.

In testimony whereof I affix my signature in presence of two witnesses.

ELSAMUR S. FRENCH.
